UNITED STATES PATENT OFFICE.

LESLIE S. CUSHMAN, OF EDEN, CALIFORNIA.

CULTIVATING TRACTOR.

Application filed October 3, 1927. Serial No. 223,757.

This invention relates to a cultivating tractor, one of the objects being to provide a single steering wheel which, when actuated, will cause the front wheels of the machine 5 and the cultivating element to shift synchronously, the machine being maintained in the proper path by the driver who can watch the position of the cultivating element without paying any attention to the positions of the 10 front wheels.

A further object is to provide means whereby the front wheels can be turned independently of the movement of the cultivating element, said wheels being so mounted as to be 15 movable through 180°, thereby enabling the machine to be turned to the right or to the left in a circle about one or the other of the rear or driving wheels.

Another object is to provide a machine all 20 of the wheels of which can be adjusted vertically, thereby to adapt the machine to the slope of the ground or the depth of the furrows and consequently maintain the machine substantially level, and allowing the machine 25 to be so adjusted as to travel with its frame as close to the ground as the nature of the work will permit.

With the foregoing and other objects in view which will appear as the description 30 proceeds, the invention resides in the combination and arrangement of parts and in the details of construction hereinafter described and claimed, it being understood that changes 35 in the precise embodiment of the invention herein disclosed may be made within the scope of what is claimed, without departing from the spirit of the invention.

In the accompanying drawings the preferred form of the invention has been shown.

40 In said drawings,

Figure 1 is a side elevation of the machine.

Figure 2 is a top plan view thereof, the motor being removed.

Figure 3 is an enlarged front elevation, a 45 portion being shown in section.

Figure 4 is an elevation of one of the spindles of the rear wheels, a portion of the structure engaged thereby being shown in section.

Figure 5 is an enlarged side elevation of the 50 front end portion of one of the cultivator beams and adjacent parts.

Figure 6 is an enlarged section on line 6—6, Figure 2.

Figure 7 is a view showing more or less in 55 diagram the connection between the shaft of the steering wheel and the cultivator beam.

Figure 8 is a section through one of the brakes.

Figure 9 is a section on line 9—9, Figure 8.

Figure 10 is a rear elevation of one of the 60 yokes, the bracket connected thereto being in section and a portion of the shaft being shown.

Referring to the figures by characters of 65 reference 1 designates the frame of the machine provided at the front end thereof with depending extensions 2 each having upper and lower bearing members 3 and 4 respectively projecting laterally therefrom. Connected to and rotatably mounted between 70 these upper and lower bearing members are yokes 5 each having a longitudinal series of apertures 6 extending transversely therethrough. Any one of these apertures is adapted to receive a threaded stem 7 extending 75 from the inner end of a spindle 8 supported by one of the front wheels 9 of the machine. Each stem is adapted to be clamped in place by a nut 10 or the like as shown in Figure 3. The upper end of each 80 yoke 5 has a short shaft 11 extending therefrom constituting the upper pivot of the yoke and secured to this shaft is a sheave 12 adapted to rotate therewith and provided with a peripheral groove. Each sheave is 85 pivotally connected as at 13 to a cross bar 14. Thus it will be seen that when one of the wheels 9 is turned the other wheel will be correspondingly turned.

Depending from the sides of the frame 1 90 near the rear end thereof are wings 15 each of which has an arcuate slot 16 concentric with the axis of rotation of a drive shaft 17 extending transversely of the frame 1. This shaft is preferably mounted for rotation in 95 a housing 18 secured on the frame 1 and which housing includes a differential indicated generally at 19.

Secured to each end of the shaft 17 is a 100 sprocket 20 and likewise secured to each end portion of the shaft is a brake including a drum 21 preferably disposed within a housing 22 and extending around an expandible friction ring 23 anchored as at 24 to the housing 22. This brake is of the usual construction, the free ends of the band being adapted to be shifted apart by the actuation of a cam 25 connected to a rotatable shaft 26 which, in turn, is adapted to be actuated by a hand lever 27 connected by a rod 28 to a crank arm 29 on the shaft 26. Each sprocket 20 drives a chain 30 which engages the 105 110

sprocket 31 secured to and rotatable with one of the supporting wheels 32. Each of these supporting wheels is journaled on a spindle 33 which, as shown in Figures 1 and 4, has a threaded stem 34 extending through the slot 16 and adapted to be clamped therein by means of a nut 35. Thus it will be seen that either or both of the wheels 32 can be adjusted angularly about the shaft 17 without interfering with the transmission of motion from said shaft to the wheel.

Extending transversely of and secured to the frame 1 is a shaft 36 on which yokes 37 are mounted. Each yoke has an integral bracket 38 carrying a sheave 39 and pivotally connected to each yoke 37 is the front forked end 40 of a cultivator beam 41. This forked end is connected to the yoke as shown at 42 in Figure 5. Beam 41 is extended rearwardly and can be of any desired construction, any suitable cultivating element indicated at 42 being connected to this beam. In the structure illustrated two of these beams have been illustrated, the same being connected by a transverse connecting yoke 43 pivotally attached to the beam but constituting means for insuring simultaneous lateral movement of the beam.

Rigidly connected to sleeves 37' on the outer sides of the yokes 37 are brackets 44 each of which carries a sheave 45. These sheaves are located between the wheels 32 and the beams 41. Both sheaves are engaged by cables 46 attached to the beams 41 and extending laterally to and partly around the sheaves 45. From these sheaves the cables are extended forwardly and upwardly into engagement with guide sheaves 39 and thence toward each other under and in engagement with a pair of sheaves 47 mounted in a bracket 48. The two cables 46 cross upwardly between the sheaves and are connected to the ends of the chain 49 which is mounted on and engages a sprocket 50. This sprocket is secured to a sleeve 51 through which is extended a steering shaft 52. A steering wheel 53 is connected to the back end portion of the shaft 52. A clutch member 54 is slidable on and rotatable with shaft 52 and is adapted to be shifted by lever 55 or the like so as to move into or out of engagement with the sleeve 51. It will be obvious that when the clutch member 54 is in engagement with the sleeve 51 rotation of shaft 52 will result in rotation of the sprocket 50 and, consequently, the chain 49 will be actuated so as to pull on one or the other of the cables 46 and cause the beams 41 to swing to the right or to the left.

Another sprocket 56 is secured to the shaft 52 so as to rotate therewith at all times and this sprocket engages a chain 57 the ends of which are attached to cables 58 which extend downwardly and forwardly under guide sheaves 59. From these sheaves the cables

cross forwardly between a pair of sheaves 60 carried by the front end portion of the frame 1 and extend laterally into engagement with and around the sheave 12. Each cable is fixedly connected to one of the sheaves 12 as indicated at 61 so that when the cables are actuated the two sheaves 12 will be caused to rotate simultaneously in the same direction. For the purpose of maintaining the cables 57 taut there may be provided with suitable tightening means such as turnbuckles 62.

The motor of the machine has been indicated generally at 63 and is adapted to transmit motion through a shaft 64 to the differential 19.

A seat for the driver has been indicated at 65 and is so located that the occupant can have ready access to the steering wheel 53 and to the levers 27 as well as to the lever 66 controlling the transmission. Seat 65 is also positioned where the occupant can easily watch the cultivating element 42 while in use.

By carefully examining the arrangement of sprockets, chains and cables it will be noted that when the shaft 52 is turned to swing wheels 9 to the left, the connections between said shaft and the beams will also swing said beams 41 to the left. Thus as the machine is travelling forwardly the operator need only watch the positions of the cultivating elements 42. Should these become positioned too far to the right of the furrows, hills or the like, it merely becomes necessary for the driver to turn the wheel 53 so that the cable 46 at the left of the machine will be pulled. This will cause the cultivating elements to swing to the left and at the same time the steering mechanism will be actuated to swing the wheels 9 to the left. This will cause the entire machine to veer toward the left and as the cultivating elements reach their proper positions and it is then desired to continue them in its movement straight forward the operator manipulates the wheel 52 so as to gradually shift the cultivating elements to the right relative to the frame 1 which, obviously, will at the same time gradually turn the wheels 9 to the right until they are pointed straight ahead and the machine can then travel forwardly. It is unnecessary for the driver to pay any attention to the positions of the wheels 9. By watching the cultivating elements and shifting them so as to maintain them at the proper positions relative to the hills or furrows, the wheels 9 will take care of themselves and cause the machine to travel in the proper direction.

When the end of the field is reached and it is desired to turn the machine, the operator shifts the clutch member 54 so as to disengage it from the sleeve 51. Thus when the shaft 52 is rotated the cultivating elements will not be shifted laterally. By means of the steering wheel 53 the sheaves 12 can be rotated through 180° to bring the wheels 9 into positions at right angles to their

straight forward positions as indicated by broken lines in Figure 2. Should it be desired to make an abrupt turn to the left the operator pulls the brake lever 27 at the left 5 of the machine. This will expand the brake member 23 against the drum 21 and hold the left hand sprocket 20 and its shaft 17 against rotation. By then applying power the 10 sprocket 20 at the other side of the machine will transmit motion through its chain 30 to the sprocket 31 engaged thereby so that the right-hand wheel 32 will become the sole 15 drive wheel and the machine will thus be turned to the left in a circle with the left wheel 32 as the center. By reversing this operation the machine can be caused to turn to the right.

By having wheels 9 and 32 which are adjustable upwardly and downwardly relative to the frame 1, said frame can be supported 20 close to the ground where it will not readily upset and where it will be particularly well situated when the machine is used for pulling 25 plows and heavy loads.

What is claimed is:

25 1. In a machine of the class described the combination with a frame including drive wheels and guide wheels mounted for swinging about upwardly extending axes, of tool beams mounted to swing laterally about individual axes, said beams being connected to the frame, a steering wheel, flexible driving connections between the steering wheel and the tool beams and between the steering wheel and the guide wheels, guides mounted on the 30 frame, and additional guides adjacent to and movable with the tool beams, all of said guides being provided for said connections whereby 35 rotation of the steering wheel in one direction will simultaneously turn said guide wheels to 40 guide the machine in that direction and swing the tool beams in said direction about their individual axes.

2. In a machine of the class described the combination with a frame, drive wheels therefor, and guide wheels mounted to swing about upwardly extending axes, of wheels concentric with the respective axes and adapted,

when rotated, to swing the respective guide wheels to steer the machine, tool beams pivotally connected to the frame at points back of 50 the guide wheels and mounted to swing laterally relative to the frame about individual axes, a steering shaft, a flexible driving connection between said shaft and the actuating 55 wheels of the guide wheels, a flexible driving connection between said shaft and the respective tool beams, guides mounted on the frame, and additional guides adjacent to and movable with the tool beams, all of said guides being provided for said connections whereby, 60 when the steering shaft is turned in one direction, the guide wheels will be swung simultaneously to direct the machine toward that side and the tool beams will be swung toward 65 said side relative to the frame.

3. In a machine of the class described the combination with a frame, drive wheels therefor, and guide wheels mounted to swing about upwardly extending axes, of wheels concentric with the respective axes and adapted, 70 when rotated, to swing the respective guide wheels to steer the machine, tool beams pivotally connected to the frame at points back of 75 the guide wheels and mounted to swing laterally relative to the frame about individual axes, a steering shaft, a flexible driving connection between said shaft and the actuating wheels of the guide wheels, a flexible driving connection between said shaft and the respective tool beams, guides for said 80 connections whereby, when the steering shaft is turned in one direction, the guide wheels will be swung simultaneously to direct the machine toward that side and the tool beams will be swung toward 85 said side relative to the frame, means within said connections for taking up slack, and means on the steering shaft for coupling or uncoupling the flexible connections of the means relative to the steering shaft.

In testimony that I claim the foregoing as my own, I have hereto affixed my signature.

LESLIE S. CUSHMAN.
